UNITED STATES PATENT OFFICE

105,482

DESIGN FOR A COMBINED INK AND PENCIL ERASER

Eberhard L. Faber, New York, N. Y., assignor to Eberhard Faber Pencil Co., Brooklyn, N. Y., a corporation of New York

Application April 12, 1937, Serial No. 68,682

Term of patent 14 years

To all whom it may concern:

Be it known that I, Eberhard L. Faber, a citizen of the United States and a resident of New York city, in the county of New York and State of New York, have invented a new, original, and ornamental Design for a Combined Ink and Pencil
Eraser, of which the following is a specification, reference being had to the accompanying drawing, forming part thereof.

bined ink and pencil eraser showing my new design, and

Figure 2 is a side elevational view thereof.

I claim:

The ornamental design for a combined ink and pencil eraser as shown.

EBERHARD L. FABER.
